(57) **ABSTRACT**

An object of the present invention is to provide a working method of an orifice, which has excellent working accuracy and high productivity in order to work an inclination portion (tapered portion) on the entire circumference of an inner wall of an orifice. Therefore, a working method of an orifice includes a first step of forming an orifice hole **54d** in an orifice forming member, a second step of pressing a downstream end surface of the orifice forming member in which the orifice hole **54d** opens, in a direction toward an upstream side of the orifice hole **54d** by a punch **46** having a cutting blade portion **46a** larger than a cross section of the orifice hole **54d**. The second step causes a material of the orifice forming member to flow from an entire circumference at the downstream end portion of the orifice hole **54d** to an inside of the orifice hole **54d** to form a cross-sectional area reduction portion **54s** in which a cross-sectional area of the orifice hole **54d** is reduced from an upstream side to a downstream side.

WORKING METHOD OF ORIFICE AND FUEL INJECTION VALVE

TECHNICAL FIELD

The present invention relates to a fluid injection valve that injects a fluid, and particularly relates to a shape of an injection portion suitable for a fuel injection valve of a cylinder injection type internal combustion engine and a working method of the injection portion.

BACKGROUND ART

As exhaust gas regulations and fuel consumption regulations for automobiles are strengthened, further reduction of particulate matter (PM) in an exhaust gas and particulate number (PN) of exhaust fine particles becomes an object.

In the fuel injection valve of a cylinder injection type internal combustion engine, a tip end portion as a fuel injection portion is mounted inside a combustion chamber. Thus, soot and the like generated by combustion may be likely to be accumulated, and fuel may remain in the accumulated soot, and thus thick combustion that causes generation of soot may be caused.

There is US 2016/0319792 A (PTL 1) as a document considering reduction of the PM and the PN. An injection portion of a fuel injection valve in PTL 1 includes a first portion formed between an inlet opening of the injection portion and an intermediate portion where a second opening is formed, and a second portion formed between the intermediate portion and an outlet opening of the injection portion (paragraph 0021). PTL 1 discloses that the first portion forms a conical shape with a cut tip end and is formed so that the cross-sectional area decreases from the inlet opening of the injection portion to the intermediate portion (paragraph 0041). A bottom surface of the second portion is formed in the intermediate portion where a second opening is formed, and the bottom surface of the second portion is worked to have a larger diameter than the second opening (FIG. 2). Further, PTL 1 discloses that the second portion forms a conical shape with a cut tip end, and is formed so that the cross-sectional area increases from the intermediate portion (the bottom surface of the second portion) to the inlet opening of the injection portion (paragraph 0045).

In addition, there is JP 2007-51573 A (PTL 2) as a document in which an orifice is formed by press working using a punch. In the working method of an orifice in PTL 2, a downstream end surface of the orifice is coined by a punch having a coining portion, so that an inclination portion inclined toward the center of the orifice is worked in $\frac{1}{2}$ of the inner wall of the orifice in a circumferential direction (paragraphs 0020 to 0021).

Patent Literature

PTL 1: US 2016-0319792 A

PTL 2: JP 2007-51573 A

SUMMARY OF INVENTION

Technical Problem

In the injection portion in PTL 1, the first portion of the injection portion is formed in a conical shape tapered toward

the downstream side between the inlet opening of the injection portion and the intermediate portion where the second opening is formed. That is, the entirety of the orifice is formed in a conical shape.

Generally, manufacturing of an orifice plate for forming an orifice includes a plurality of working steps, and dimensional errors of an orifice plate material and working errors occurring in the respective working steps are stacked, and it is difficult to manage the axial length of the first portion (orifice) with high accuracy. In this case, since the first portion (orifice) is formed in a conical shape, the diameter of the inlet opening of the injection portion or the diameter of the second opening changes due to variations in the axial length of the first portion (orifice), and there is a possibility that the injection amount varies.

In addition, PTL 1 does not consider a working method of an orifice. On the other hand, PTL 2 discloses a working method of an orifice using press working. However, in PTL 2, for the purpose of increasing the spread of the spray, an inclination portion is worked on a portion of the inner wall of the orifice in the circumferential direction.

An object of the present invention is to provide a working method of an orifice, which has excellent working accuracy and high productivity in order to work an inclination portion (tapered portion) on the entire circumference of an inner wall of an orifice, and a fuel injection valve.

Solution to Problem

In order to achieve the above object, according to the present invention, a working method of an orifice includes a first step of forming an orifice hole in an orifice forming member, a second step of pressing a downstream end surface of the orifice forming member in which the orifice hole opens, in a direction toward an upstream side of the orifice hole by a punch having a cutting blade portion larger than a cross section of the orifice hole. The second step causes a material of the orifice forming member to flow from an entire circumference at a downstream end portion of the orifice hole to an inside of the orifice hole to form a cross-sectional area reduction portion in which a cross-sectional area of the orifice hole is reduced from an upstream side to a downstream side.

In addition, in order to achieve the above object, according to the present invention, a fuel injection valve includes an orifice forming member in which an orifice hole is formed. The orifice forming member includes a cross-sectional area reduction portion having a cross-sectional area that is reduced from a first inner circumferential surface on an upstream side of the orifice hole toward a downstream side, a first recess portion that is formed on a downstream side of the cross-sectional area reduction portion and has an inner diameter larger than the minimum inner diameter of the cross-sectional area reduction portion, and a second recess portion that is formed on a downstream side of the first recess portion and has an inner diameter larger than the inner diameter of the first recess portion.

Advantageous Effects of Invention

According to the present invention, it is possible to provide a working method of an orifice, which has excellent working accuracy and high productivity in order to work an inclination portion (tapered portion) on the entire circumference of an inner wall of an orifice, and a fuel injection valve.

Objects, configurations, and advantageous effects other than those described above will be clarified by the descriptions of the following embodiments.

BRIEF DESCRIPTION OF DRAWINGS

FIG. 1 is a cross-sectional view illustrating a cross section parallel to a center axis of a fuel injection valve according to an example of the present invention.

FIG. 2 is a perspective view of an orifice plate according to an example of the present invention.

FIG. 3 is a cross-sectional view illustrating a cross section parallel to a center axis of the orifice plate according to the example of the present invention.

FIG. 4 is a flowchart illustrating a working step of the orifice plate according to the example of the present invention.

FIG. 5 is a cross-sectional view illustrating a cross section parallel to a center axis of an orifice plate blank according to the example of the present invention.

FIG. 6 is a cross-sectional view after a positioning hole is worked in the orifice plate illustrated in FIG. 5.

FIG. 7 is a cross-sectional view after an opening portion A is worked in the orifice plate illustrated in FIG. 6.

FIG. 8 is a cross-sectional view after an opening portion B is worked in the orifice plate illustrated in FIG. 7.

FIG. 9 is a cross-sectional view after an orifice is worked in the orifice plate illustrated in FIG. 8.

FIG. 10 is a cross-sectional view after an opening portion C and a tapered portion are worked in the orifice plate illustrated in FIG. 9.

FIG. 11 is a cross-sectional view after a seat surface is rough-worked in the orifice plate illustrated in FIG. 9.

FIG. 12 is a cross-sectional view after the seat surface is finished in the orifice plate illustrated in FIG. 9.

FIG. 13 is a cross-sectional view illustrating press working of the positioning hole according to the example of the present invention.

FIG. 14 is a cross-sectional view illustrating press working of the opening portion A according to the example of the present invention.

FIG. 15 is a cross-sectional view illustrating press working of the opening portion B according to the example of the present invention.

FIG. 16 is a cross-sectional view illustrating press working of the orifice according to the example of the present invention.

FIG. 17A is a cross-sectional view illustrating press working of the opening portion C and the tapered portion according to the example of the present invention.

FIG. 17B is an enlarged cross-sectional view illustrating a vicinity of the opening portion C and the tapered portion in the press working of FIG. 17A.

FIG. 18A is an enlarged cross-sectional view illustrating a state after an orifice 57 is worked, in order to describe an object in the press working of the orifice.

FIG. 18B is an enlarged cross-sectional view illustrating the state after the orifice 57 is worked, in order to describe the object in the press working of the orifice.

FIG. 19 is a graph showing a relation between a depth of the opening portion C and a diameter of the tapered portion according to the example of the present invention.

FIG. 20 is a view illustrating the tapered portion of the orifice in detail.

DESCRIPTION OF EMBODIMENTS

Hereinafter, examples of the present invention will be described in detail with reference to the drawings.

FIG. 1 is a cross-sectional view illustrating a cross section parallel to a center axis of a fuel injection valve according to an example of the present invention. A fuel injection valve 1 in the present example is a fuel injection valve that injects fuel such as gasoline, and is used to inject fuel to an engine of an automobile.

The fuel injection valve 1 includes a magnetic circuit including a core 2, a yoke 3, a housing 4, and a mover 5, a coil 6 that excites the magnetic circuit, and a terminal 7 that energizes the coil 6. A seal ring 8 is coupled between the core 2 and the housing 4 to prevent a fluid such as fuel from flowing into the coil 6.

A valve component is housed inside the housing 4, and the mover 5, a nozzle holder 9, and a ring 10 for adjusting the stroke amount of the mover 5 are disposed. The mover 5 is formed by coupling a valve body 11 and a movable core 12 by a joint 13, and includes a plate 14 that suppresses a bound when the mover 5 is closed in cooperation with a pipe 18 between the movable core 12 and the joint 13.

The housing 4 and the nozzle holder 9 constituting an outer coat member cover the periphery of the mover 5.

The nozzle holder 9 is provided with an orifice plate (orifice forming member) 15 having a seat surface 15a (valve seat) and orifices 54 to 59 at the tip end, and a guide plate B (second guide member) 17 that slidably guides the mover 5 together with a guide plate A (first guide member) 16. The orifice plate 15 and the guide plate B 17 may be configured as separate members from the nozzle holder 9, or may be configured by integrating these members.

A spring 19 that presses the valve body 11 against the seat surface 15a via the pipe 18 and the plate 14, an adjuster 20 that adjusts a pressing load of the spring 19, and a filter 21 that prevents intrusion of contamination from the outside are disposed inside the core 2.

Next, an operation of the fuel injection valve 1 will be described in detail.

When the coil 6 is energized, the mover 5 is attracted toward the core 2 against the biasing force of the spring 19, and a gap is formed between the valve seat portion 11a at the tip end of the mover 5 and the seat surface 15a (valve open state). The pressurized fuel first enters the nozzle holder 9 from the core 2, the adjuster 20, and the pipe 18 through the fuel passage 13a in the mover 5. Then, the fuel enters into the passage 17a of the guide plate B from the fuel passage 16a of the guide plate A 16 and the passage 9a of the nozzle holder, and is injected from the gap between the valve seat portion 11a and the seat surface 15a through the orifices 54 to 59.

The orifices 54 to 59 are formed at a different inclination angle in a direction inclined with respect to the center axis 1a of the fuel injection valve.

On the other hand, when the current of the coil 6 is cut off, the valve seat portion 11a of the mover 5 abuts on the seat surface 15a by the force of the spring 19, and the valve is closed.

Next, the configurations of the orifice plate 15 and the orifices 54 to 59 in the fuel injection valve 1 will be described in detail.

FIG. 2 is a perspective view of the orifice plate according to the example of the present invention. FIG. 3 is a cross-sectional view illustrating a cross section parallel to the center axis of the orifice plate according to the example of the present invention.

The orifice plate 15 is made of a substantially disk-shaped metal plate, a spherical portion 30 as a convex curved surface portion is integrally provided at a substantially central portion of one end surface, and a substantially

conical seat surface **15a** constituting a valve seat is provided on the other end surface (opposite end surface) of the spherical portion **30**.

In the spherical portion **30**, orifices **54, 55, 56, 57, 58**, and **59** for injecting fuel are formed in a direction having an angle θ_{Ax} with respect to the center axis **1a** of the fuel injection valve **1**, in other words, in an inclined direction. The respective orifices **54, 55, 56, 57, 58**, and **59** are formed to have different inclination angles θ_{Ax} , and are arranged in a predetermined direction with respect to the positioning holes **31a, 31b**, and **31c**.

The cross-sectional shapes of the orifices **54** to **59** are basically the same as each other, and the orifice will be described using the cross-sectional shape of the orifice **54** in FIG. 1 as a representative.

The orifice **54** is inclined with respect to the center axis **1a** of the fuel injection valve **1**, and is opened on a substantially conical seat surface **15a**. Therefore, the orifice **54** has a curved upstream inlet portion (inlet opening surface), has an orifice cylindrical portion (orifice hole) **54d** having a cylindrical shape from the inlet portion of the orifice **54** toward the downstream side, becomes a tapered portion **54s** tapered from the middle toward the outlet opening portion (outlet opening surface) of the orifice **54**, and a terminal end of the tapered portion **54s** has a substantially minimum diameter.

Circular opening portions A (third opening portions) **54a, 55a, 56a, 57a, 58a**, and **59a** that form steps are provided on the side opening to the spherical portion **30** that is the downstream portion of the orifices **54** to **59**. Opening portions B (second opening portions) **54b, 55b, 56b, 57b, 58b**, and **59b** having a smaller diameter than the opening portions **A54a** to **59a** and having a circular shape are provided on a side connected to the orifices **54** to **59**, which is an upstream side thereof. That is, the opening portions **B54b** to **59b** are provided at the bottom of the opening portion A. Further, on the upstream side, circular opening portions C (first opening portions) **54c, 55c, 56c, 57c, 58c**, and **59c** having smaller diameters than the opening portions **B54b** to **59b** are provided. That is, the opening portions **C54c** to **59c** are provided at the bottom of the opening portion B. The openings form three steps as a whole by the opening portions **A54a** to **59a**, the opening portions **B4b** to **59b**, and the opening portions **C54c** to **59c**. The injection portion includes the orifices **54** to **59** and the opening portions **54a** to **59a**, **54b** to **59b**, and **54c** to **59c**.

The opening portions **A54a, 55a, 56a, 57a, 58a**, and **59a**, the opening portions **B54b, 55b, 56b, 57b, 58b**, and **59b**, and the opening portions **C54c, 55c, 56c, 57c, 58c**, and **59c** have a concave hole shape when viewed from the downstream side, and thus may be referred to as a recess portion.

The bottom surfaces of the opening portions **A54a** to **59a** and the opening portions **B54b** to **59b** are formed to be surfaces substantially perpendicular to the center axis line **Ax** of the orifice, and the center axis line **Bx** of the opening portion A and the opening portion B and the center axis line **Ax** of the orifice are substantially straight.

Since the length of the orifice is highly sensitive to the length of the spray penetration, for example, in order to optimally set the length of the orifice **54** in consideration of the spray shape and workability, the depth of the opening portion **B54b** can be appropriately changed. The same applies to other orifices. The length of the orifice can be changed by changing the depth of the opening portion B, and the spray shape can be optimized and the workability can be improved. Therefore, at least two of the opening portions B have different depths for each orifice.

With the orifice shape as described above, the fuel rapidly changes the flow direction from the gap between the valve seat portion **11a** and the seat surface **15a** and flows into the orifice **54**, and becomes a flow biased toward the center axis **1a** side inner wall of the fuel injection valve **1** in the orifice cylindrical portion **54d**. However, the fuel is rectified by the orifice cylindrical portion **54d**, further assembled while changing the direction in the center axis **Ax** direction of the orifice **54** by the tapered portion **54s**, pressurized and accelerated, and injected into the engine cylinder through the opening portion C, the opening portion B, and the opening portion A.

As described above, since the fuel changes its direction in the center axis **Ax** direction of the orifice at the tapered portion and gathers, and is pressurized and accelerated, the fuel does not interfere with the opening portion C, the opening portion B, and the inner walls of the opening portion A, and hardly adheres to the opening portion C, the opening portion B, and the inner walls of the opening portion A, and further the adhesion to the spherical portion **30** can be reduced.

Next, a flow of a working method of the orifice plate **15** will be described with reference to FIGS. 4 to 12.

FIG. 4 is a flowchart illustrating a working step of the orifice plate according to the example of the present invention. FIG. 5 is a cross-sectional view illustrating a cross section parallel to the center axis of an orifice plate blank according to the example of the present invention. FIG. 6 is a cross-sectional view after the positioning hole is worked in the orifice plate illustrated in FIG. 5. FIG. 7 is a cross-sectional view after the opening portion A is worked in the orifice plate illustrated in FIG. 6. FIG. 8 is a cross-sectional view after the opening portion B is worked in the orifice plate illustrated in FIG. 7. FIG. 9 is a cross-sectional view after the orifice is worked in the orifice plate illustrated in FIG. 8. FIG. 10 is a cross-sectional view after the opening portion C and the tapered portion are worked in the orifice plate illustrated in FIG. 9. FIG. 11 is a cross-sectional view after the seat surface is rough-worked in the orifice plate illustrated in FIG. 9. FIG. 12 is a cross-sectional view after the seat surface is finished in the orifice plate illustrated in FIG. 9.

In Step S1, a blank **15'** of the orifice plate **15** is machined. The blank **15'** has a shape as illustrated in FIG. 5.

After Step S1, Step S2 of press working an injection portion is performed. In this press working, first, a working step S201 of the positioning holes **31a** to **31c** is performed. The orifice plate **15** having the positioning holes **31a, 31b**, and **31c** is formed by the working step S201 as illustrated in FIG. 6.

After the working step S201, a working step S202 (fourth step) of opening portions **A54a** to **59a** is performed. The orifice plate **15** having the opening portions **A54a** to **59a** as illustrated in FIG. 7 is formed by the working step S202.

After the working step S202, a working step S203 (third step) of opening portions **B54b** to **59b** is performed. The orifice plate **15** having the opening portions **B54b** to **59b** as illustrated in FIG. 8 is formed by a working step S203.

After the working step S203, a working step S204 (first step) of the cylindrical portions **54d** and **57d** (the reference signs **55d, 56d, 58d**, and **59d** are not illustrated, and thus the reference signs **54d** and **57d** are used here) of the orifice is performed. As illustrated in FIG. 9, the orifice plate **15** having the cylindrical portions **54d** and **57d** (the reference signs **55d, 56d, 58d**, and **59d** are not illustrated, and thus the reference signs **54d** and **57d** are used here) of the orifice is formed by the working step S204.

A working step S205 of the opening portions C54c to 59c is performed after the working step S204. With the working step S205 (second step), as illustrated in FIG. 10, the orifice plate 15 having the opening portions C54c to 59c and the tapered portions 54s and 57s (the reference signs 55s, 56s, 58s, and 59s are not illustrated, and thus the reference signs 54s and 57s are used here) is formed. The configurations of the tapered portions 54s and 57s will be described in detail with reference to FIG. 20.

After Step S2, Step S3 of performing rough working of the seat surface 15a is performed. By the working step S3, the orifice plate 15 having the seat surface 15a subjected to rough working as illustrated in FIG. 11 is formed.

After Step S3, Step S4 of quenching the orifice plate 15 is performed.

After Step S4, Step S5 of finishing the seat surface 15a is performed. By the working step S5, the orifice plate 15 having the seat surface 15a subjected to finish processing as illustrated in FIG. 12 is formed.

Next, each working step of the orifice plate 15 will be described in detail with reference to FIGS. 13 to 17B.

The blank 15' illustrated in FIG. 5 is manufactured by machining or plastically working a disk-shaped member having a spherical portion 30 at the central portion of one end surface. Further, a bowl-shaped recess 29 is formed on an end surface of the blank 15' opposite to the spherical portion 30.

Next, press working of the injection portion (fuel injection portion) will be described.

In this step, the positioning holes 31a, 31b, and 31c, the opening portions A54a to 59a, the opening portions B54b to 59b, and the orifices 54 to 59 are continuously subjected to press working while chucking the blank 15'.

FIG. 13 is a cross-sectional view illustrating press working of the positioning hole according to the example of the present invention. As illustrated in FIG. 13, the blank 15' having the spherical portion 30 formed thereon is installed on the upper surface of the die 41, and the outer diameter is firmly held by the collet chuck 42. Further, the outer peripheral side of the spherical portion 30 is pressed by a cutting blade portion 40a of the punch 40 while holding the blank 15', and the positioning hole 31a is worked.

Similarly, the positioning holes 31b and 31c are worked. As described above, by forming the positioning holes 31a, 31b, and 31c in the blank 15' by press working, the orifice plate 15 having the positioning holes 31a, 31b, and 31c at three positions on the outer peripheral side of the spherical portion 30 as illustrated in FIG. 2 is obtained.

Then, press working illustrated in FIG. 14 is performed. FIG. 14 is a cross-sectional view illustrating press working of the opening portion A according to the example of the present invention.

In a state where the orifice plate 15 is held by the collet chuck 42, the spherical surface portion 30 is pressed by a cutting blade portion 43a of a punch 43, and the opening portion A54a is extruded into a bag hole shape. Similarly, the opening portions A55a, 56a, 57a, 58a, and 59a are worked. Note that the working of the opening portion A may mean press working and work-hardening of the surface. As described above, by forming the opening portion A in the orifice plate 15 by press working, the opening portion A having a surface roughness Rz of 0.2 μm or less having a surface substantially perpendicular to the center axis Bx of the opening portion A is formed in the spherical portion 30 as illustrated in FIG. 7.

Then, press working illustrated in FIG. 15 is performed. FIG. 15 is a cross-sectional view illustrating press working of the opening portion B according to the example of the present invention.

5 While the orifice plate 15 is held by the collet chuck 42, the bottom surface of the opening portion A54a is pressed by a cutting blade portion 44a of a punch 44 from the same direction as the punch 43 forming the opening portion A, and the opening portion B54b is extruded into a bag hole shape.

10 Similarly, the opening portions B55b, 56b, 57b, 58b, and 59b are worked, but the order of working is appropriately determined depending on the deflection direction of the orifice. Note that the processing of the opening portion B may mean press working and work-hardening of the surface.

15 As described above, by forming the opening portion B in the orifice plate 15 by press working, the orifice plate 15 having the opening portion B having the surface roughness Rz of 0.2 μm or less on the bottom surface of the opening portion A as illustrated in FIG. 8 is obtained.

20 Then, press working illustrated in FIG. 16A is performed. FIG. 16A is a cross-sectional view illustrating press working of the orifice according to the example of the present invention.

In a state where the orifice plate 15 is held by the collet 25 chuck 42, a cutting blade portion 45a of a punch 45 is pressed perpendicularly to the bottom surface portion of the opening portion B54b, and the orifice 54 is extruded into a bag hole shape. Similarly, the orifices 55, 56, 57, 58, and 59 are worked, but the order of working is appropriately

30 determined depending on the deflection direction of the orifices. As described above, by forming the orifice in the orifice plate 15 by press working, the orifice plate 15 having the orifice on the bottom surface of the opening portion B as illustrated in FIG. 9 is obtained. Since the orifice plate 15 is held by the collet chuck 42, the orifice plate is worked with high positional accuracy so that the opening portion A, the opening portion B, and the center axes Ax and Bx of the orifices are substantially aligned with reference to the positioning holes 31a, 31b, and 31c. In addition, the orifice can have an inner surface processed into an entire molding surface by being press-worked into a bag hole shape, and

35 can have a surface roughness Rz of 0.2 μm or less without a fracture surface or the like.

40 Then, press working illustrated in FIGS. 17A and 17B is performed. FIG. 17A is a cross-sectional view illustrating press working of the opening portion C and the tapered portion according to the example of the present invention. FIG. 17B is an enlarged cross-sectional view illustrating the vicinity of the opening portion C and the tapered portion in 50 the press working of FIG. 17A.

In a state where the orifice plate 15 is held by the collet chuck 42, a cutting blade portion 46a of a punch 46 is pressed at a right angle to the bottom surface portion 54b1 of the opening portion B54b to mold the opening portion C54c, and the material is caused to flow to the radial center side of the orifice 54 in the vicinity of the downstream opening portion 54do of the orifice 54 to mold the tapered portion 54s. At this time, the orifice 54 includes an orifice cylindrical portion 54d and a tapered portion 54s. Similarly, the opening portions C55c, 56c, 57c, 58c, and 59c and the tapered portions 55s, 56s, 57s, 58s, and 59s are worked, but the order of working is appropriately determined depending on the deflection direction of the orifice. As described above, by forming the tapered portion on the orifice plate 15 by press working, the orifice plate 15 having the opening portion C and the tapered portion on the bottom surface of the opening portion B as illustrated in FIG. 10 is obtained.

Since the tapered portion has a tapered shape in which the cross-sectional area decreases from the upstream side to the downstream side, the tapered portion can also be referred to as a tapered portion or a cross-sectional area reduction portion. Note that the cross-sectional area in this case is an area of a cross section perpendicular to the center axis Ax. In addition, since the tapered portion constitutes a portion having the smallest cross-sectional area in the injection portion, the tapered portion may be referred to as a tapered throttle portion.

Here, features of the orifice at the time of press working will be described with reference to FIGS. 18A and 18B.

FIG. 18A is an enlarged cross-sectional view illustrating a state after the orifice 57 is worked, in order to describe the object in the press working of the orifice. Although the orifice 57 is described as an example in FIG. 18A, the same applies to other orifices.

When the surface is not work-cured at the time of press working of the opening portion B, or when the degree of work curing is small, shear droop 57e is generated at an opening edge portion formed on the inlet side of the punch 45 at the time of press working of the orifice. When the shear droop 57e remains in the completed orifice plate 15, the fuel flowing down through the orifice starts to spread from the portion of the shear droop 57e, and the spreading angle of the spray injected from the orifice increases.

In the present example, since the opening portion C having a diameter larger than the orifice diameter is press-worked after the press working of the orifice, the shear droop 57e is shaped by the pressing of the opening portion C and disappears. Therefore, the fuel injection valve 1 of the present example can inject a spray having a small spreading angle.

FIG. 18B is an enlarged cross-sectional view illustrating a state after the orifice 57 is worked, in order to describe the object in the press working of the orifice. Although the orifice 57 is described as an example in FIG. 18B, the same applies to other orifices.

When the plate thickness L and the punch diameter d for press working have a relation of L/d 1.5, a convex portion 57f is generated at an opening edge portion formed on the inlet side of the punch 45 during press working. In the present example, the plate thickness L is the length of the orifice 57, and the punch diameter d is the inner diameter of the orifice 57. The convex portion 57f is formed so as to rise from the bottom surface 57b1 of the opening portion B57b. Since the inlet opening surface (upstream opening surface) 57di of the cylindrical portion 57d of the orifice 57 is not orthogonal to the center axis Ax of the orifice 57, the length L of the orifice 57 is defined as follows.

L: length formed between an intersection P1 between the center axis Ax and the inlet opening surface 57di of the cylindrical portion 57d and an intersection P2 between the center axis Ax and the outlet opening surface 57do' of the cylindrical portion 57d, on the center axis Ax of the orifice 57

In this case, the cylindrical portion 57d is a cylindrical portion when the orifice 57 is extruded into a bag hole shape by the punch 45, and the orifice 57 is in a state before the opening portion C57c and the tapered portion 57s are formed. In this case, the outlet opening surface 57do' of the cylindrical portion 57d is flush with the bottom surface 57b1 of the opening portion B57b. Therefore, the definition of the length L may be the bottom surface 57b1 instead of the outlet opening surface 57do'.

In the example described above, the diameter of the cutting blade portion 46a of the punch 46 forming the

opening portion C57c and the tapered portion 57s is smaller than the diameter of the cutting blade portion 44a of the punch 44 forming the opening portion B57b. This is because the tapered portion 57s can be formed even when the bottom surface 57b1 of the opening portion B57b is a flat surface. As described with reference to FIG. 18B, when the convex portion 57f is formed on the bottom surface 57b1 of the opening portion B57b, the tapered portion 57s can be formed by plastically flowing the material of the convex portion 57f toward the radial center side of the orifice 57. In this case, the tapered portion 57s can be formed using the cutting blade portion 44a of the punch 44 forming the opening portion B57b. In this case, the opening portion C57c is not formed.

Even when the convex portion 57f is formed on the bottom surface 57b1 of the opening portion B57b, the tapered portion 57s may be formed by forming the opening portion C57c with the cutting blade portion 46a of the punch 46 having a diameter smaller than the diameter of the cutting blade portion 44a of the punch 44 for forming the opening portion B57b. In this case, the amount of the material to be plastically flowed can be increased, and the large tapered portion 57s can be formed.

FIG. 19 is a graph showing a relation between the depth of the opening portion C and the diameter of the tapered portion according to the example of the present invention.

As illustrated in FIG. 19, the depth of the opening portion C and the diameter of the tapered portion are substantially linearly correlated, and the diameter of the tapered portion decreases as the depth of the opening portion C increases.

Since the orifice plate 15 is held by the collet chuck 42, the orifice plate is worked with high positional accuracy so that the center axes Ax and Bx of the opening portion A, the opening portion B, the opening portion C, the orifice, and the reverse tapered throttle portion are substantially straight with reference to the positioning hole.

Here, since the material is extruded forward as in 15b (see FIGS. 14 and 15) when the opening portion A and the opening portion B are press-worked, the plate thickness of the orifice processing portion can be made thicker than that in the blank, and occurrence of a fracture surface can be suppressed.

In addition, since the plate thickness of the blank can be reduced, the working stress at the time of orifice processing can be reduced, the orifice accuracy can be improved, and the punch life can be improved.

Furthermore, since the orifice processing portion partially swells by extruding the opening portion A and the opening portion B (15b), the flow of the material to the adjacent orifice is alleviated when the orifice is processed, and the previously processed orifice is hardly deformed and can be processed with high accuracy. In addition, since each orifice is processed into a bag hole shape, rigidity is high, and when adjacent orifices are press-worked, the already processed orifice is hardly deformed, and processing can be performed with high accuracy. When punching is performed, the rigidity of the orifice is reduced, so that the orifice is easily deformed when the adjacent hole is punched.

After the press working illustrated in FIGS. 17A and 17B, the cabin 15d and the substantially conical seat surface 15a (valve seat) illustrated in FIG. 11 are processed. The working at this time is rough working. The extruded portion 15b formed in the recess on the opposite end surface of the spherical portion 30 by molding the orifice into a bag hole shape is removed by working the cabin 15d and the seat surface 15a (valve seat), and six orifices 54 to 59 simultaneously penetrate to the seat surface 15a side. The working method at this time is machining, electrical discharge work-

11

ing, or the like. As a result, the orifice can be formed on the entire molding surface by press working.

Then, in order to improve the wear resistance of the seat surface **15a** that becomes the collision surface of the movable valve **5**, the orifice plate **15** is subjected to vacuum quenching treatment, and for example, in the case of a material of martensitic stainless steel SUS 420J2, the hardness is set to HRC52 to 56. At this time, the orifice plate **15** is recrystallized by martensitic transformation, and the surface roughness of the opening portion A, the opening portion B, and the orifice inner surface is Rz of 2 μm or less.

Then, as illustrated in FIG. 12, the seat surface **15a** after quenching is finished by being polished to improve roundness and surface roughness, and improve oil tightness between the valve seat portion **11a** and the seat surface.

Finally, burrs generated on the upstream side of the orifice are removed by seat surface finishing, and the orifice plate is completed. Although various deburring methods are conceivable at this time, deburring at a time with a water jet or the like is preferable in terms of working cost because there are a plurality of orifices.

By manufacturing in the above steps, it is possible to manufacture a plurality of orifices and opening portions each having a cylindrical portion and a tapered portion having different deflection angles in a state where the surface roughness Rz is 2 μm or less, and variations in shape, accuracy, and surface roughness are small. In the working step of the present example, the orifice can be manufactured easily and inexpensively with high productivity.

Therefore, it is possible to further reduce adhesion of deposits such as carbon generated by combustion of fuel at the time of cylinder injection to the opening portion A, the opening portion B, the opening portion C, the orifice, and the tip end portion of the fuel injection valve positioned in the engine cylinder, and it is possible to provide a fuel injection valve having good durability capable of maintaining the performance in the initial state. In addition, it is possible to reduce the number of particles of particulate matter and exhaust fine particles in the exhaust gas.

In addition, since the method of press working the orifice having the tapered portion according to the present example can significantly suppress the capital investment as compared with the method of working the orifice by laser working, the fuel injection valve can be provided at a lower cost.

In the above-described example, the region where the opening portion A is formed has been described as the spherical surface portion **30**, but a curved surface (curved surface portion) other than the spherical surface may be used. In addition, the opening portion A may be eliminated, and only the opening portion B and the opening portion C may have a two-step shape.

FIG. 20 is a view illustrating the tapered portion of the orifice in detail. Although the orifice **57** is described in FIG. 20, the other orifices **54-56**, **58**, and **59** have the same configuration.

As illustrated in FIG. 20, a communication hole **57s1** having a substantially uniform inner diameter in the direction along the center axis **Ax** of the cylindrical portion (orifice hole) **57d** of the orifice is formed at the downstream end portion of the tapered portion (cross-sectional area reduction portion) **57s**. That is, the communication hole **57s1** is connected to the downstream end of the tapered portion **57s**, and the inner diameter of the communication hole **57s1** is the same as the minimum inner diameter of the cross-sectional area reduction portion **57s**. As illustrated in FIG. 1, in the orifice **54**, a communication hole **54s1** is

12

formed between the opening portion C (first recess portion) **54c** and the tapered portion (cross-sectional area reduction portion) **54s**.

Further, the communication holes **54s1** and **57s1** are formed along with the formation of the opening portions C (first recess portions) **54c** and **57c** and the tapered portions (cross-sectional area reduction portions) **54s** and **57s** in the working step **S205** (second step). That is, the flow of the material forms the communication holes **54s1** and **57s1**. The communication holes **54s1** and **57s1** constitute a part of the tapered portions (cross-sectional area reduction portions) **54s** and **57s**. Even if the communication holes **54s1** and **57s1** exist, the cross-sectional areas of the tapered portions (cross-sectional area reduction portions) **54s** and **57s** do not increase from the upstream side toward the downstream side. That is, the tapered portions (cross-sectional area reduction portions) **54s** and **57s** have communication holes (second inner circumferential surfaces) **54s1** and **57s1** having substantially uniform inner diameters in the direction along the center axis of the orifice hole at the downstream end portions.

In the tapered portions (cross-sectional area reduction portions) **54s** and **57s** in the present example, since an extreme acute angle portion is not formed, it is not particularly necessary to chamfer the corner portions.

Features of the above-described example will be listed below.

(1) A working method of an orifice includes a first step **S204** of forming orifice holes **54d** to **59d** in an orifice forming member **15**, a second step **S205** of pressing a downstream end surface of the orifice forming member **15** in which the orifice holes **54d** to **59d** open, in a direction toward an upstream side of the holes **54d** to **59d** by a punch **46** having a cutting blade portion **46a** larger than cross sections of the orifice holes **54d** to **59d**. The second step **S205** causes a material of the orifice forming member **15** to flow from an entire circumference at a downstream end portion of the orifice holes **54d** to **59d** to an inside of each of the orifice holes **54d** to **59d** to form cross-sectional area reduction portions **54s** and **57s** (the reference signs **55s**, **56s**, **58s**, and **59s** are not illustrated, and thus the reference signs **54s** and **57s** are used here. This is similarly applied to the following description) in which cross-sectional areas of the orifice holes **54d** to **59d** are reduced from an upstream side to a downstream side.

(2) In (1), the orifice holes **54d** to **59d** have a circular cross section.

(3) In (2), in the second step **S205**, first recess portions **54c** to **59c** are formed in the downstream opening portions of the orifice holes **54d** to **59d** together with the cross-sectional area reduction portions **54s** and **57s**, the first recess portions having an inner diameter larger than that of the orifice holes **54d** to **59d**.

(4) In (3), communication holes **54s1** and **57s1** (the reference signs **55s1**, **56s1**, **58s1**, and **59s1** are not illustrated, and thus the reference sign **57s1** is used here. This is similarly applied to the following description) having an inner diameter which is substantially uniform in the direction along the center axis **Ax** of the orifice holes **54d** to **59d** are formed between the first recess portions **54c** to **59c** and the cross-sectional area reduction portions **54s** and **57s**, and the inner diameter of the communication hole **57s1** is equal to the minimum inner diameter of the cross-sectional area reduction portions **54s** and **57s**.

13

(5) In (4), the communication hole **57s1** is formed with the formation of the first recess portions **54c** to **59c** and the cross-sectional area reduction portions **54s** and **57s** in the second step **S205**.

(6) In (3), the working method further includes a third step **S203** of forming second recess portions **54b** to **59b** having bottom surfaces in which outlet opening portions of the orifice holes **54d** to **59d** open, before the orifice holes **54d** to **59d** are formed, and the inner diameters of the second recess portions **54b** to **59b** are formed to be larger than those of the orifice holes **54d** to **59d**.

(7) In (6), the working method further includes a fourth step **S202** of forming the third recess portions **54a** to **59a** having a bottom surface in which the second recess portions **54b** to **59b** open, before the second recess portions **54b** to **59b** are formed, and the inner diameters of the third recess portions **54a** to **59a** are larger than the inner diameters of the second recess portions **54b** to **59b**.

(8) In (3), the second recess portions **54b** to **59b** are 20 press-molded in the spherical portion **30** provided at the tip end of the orifice forming member **15**, in the first step **S204**, the orifice holes **54d** to **59d** are press-worked into a cylindrical shape on the bottom surfaces of a work-hardened second recess portions **54b** to **59b**, and, in the second step 25 **S205**, the bottom surfaces of the second recess portions **54b** to **59b** in which the orifice holes **54d** to **59d** open are press-worked to form the cross-sectional area reduction portions **54s** and **57s**.

(9) In (8), when the inner diameter of the orifice hole is 30 defined as d , and a length formed between the intersection **P1** between the center axis **Ax** and the inlet opening surface **57di** (the reference signs **54di**, **55di**, **56di**, **58di**, and **59di** are not illustrated, and thus the reference sign **57di** is used here. This is similarly applied to the following description) of the 35 orifice holes **54d** to **59d** before the cross-sectional area reduction portions **54s** and **57s** are formed, and the intersection **P2** between the center axis **Ax** and the outlet opening surface **57do'** (the reference signs **54do'**, **55do'**, **56do'**, **58do'**, and **59do'** are not illustrated, and thus the reference sign **57do'** is used here. This is similarly applied to the following 40 description) of the orifice holes **54d** to **59d**, on the center axis **Ax** of the orifice holes **54d** to **59d**, is set to L , the orifice holes **54d** to **59d** are formed to satisfy a relation of $L/d \geq 1.5$.

(10) In (9), in the first step **S204**, a convex portion **57f** (the 45 reference signs **54f**, **55f**, **56f**, **58f**, and **59f** are not illustrated, and thus the reference sign **57f** is used here. This is similarly applied to the following description) that swells from bottom surfaces of the second recess portions **54b** to **59b** on the bottom surfaces of the second recess portions **54b** to **59b** in 50 a vicinity of outlet opening portions of the orifice holes **54d** to **59d** with press-working of the orifice holes **54d** to **59d**, and, in the second step **S205**, the cross-sectional area reduction portions **54s** and **57s** are formed by press-working of the convex portion **57f** into a substantially flat shape. 55

(11) A fuel injection valve **1** includes an orifice forming member **15** in which orifice holes **54d** to **59d** are formed. The orifice forming member **15** includes cross-sectional area reduction portions **54s** and **57s** having a cross-sectional area that is reduced from a first inner circumferential surface on an upstream side of the orifice holes **54d** to **59d** toward a downstream side, first recess portions **54c** to **59c** that are formed on a downstream side of the cross-sectional area reduction portions **54s** and **57s** and have an inner diameter larger than a minimum inner diameter of the cross-sectional area reduction portions **54s** and **57s**, and second recess portions **54b** to **59b** that are formed on a downstream side of 60

14

the first recess portions **54c** to **59c** and have an inner diameter larger than the inner diameter of the first recess portions **54c** to **59c**.

(12) In (11), the first inner circumferential surface is 5 formed to be a cylindrical surface.

(13) In (12), the cross-sectional area reduction portions **54s** and **57s** have a second inner circumferential surface **57S1** at the downstream end portion, the second inner circumferential surface **57S1** having a substantially uniform 10 inner diameter in the direction along the center axis **Ax** of the orifice holes **54d** to **59d**.

Note that, the present invention is not limited to the above example, and various modifications may be provided.

For example, the above example has been described in 15 detail in order to explain the present invention in an easy-to-understand manner, and the above example is not necessarily limited to a case including all the configurations. Regarding some components in the example, other components can be added and replaced.

S205 second step

The invention claimed is:
1. A working method of an orifice, the working method comprising:
a first step of pressing a punch against a bottom surface of a second recess portion of an orifice forming member to form an orifice hole smaller than an inner diameter of the second recess portion by press working; and;
a second step of pressing a downstream end surface of the orifice forming member in which the orifice hole opens, in a direction toward an upstream side of the orifice hole by a punch having a cutting blade portion larger than a cross section of the orifice hole, wherein
in the first step, a convex portion swells from a bottom surface of the second recess portion on a bottom surface of the second recess portion in a vicinity of an outlet opening portion of the orifice hole with press-working of the orifice hole, and
in the second step, the convex portion is pressed substantially flat, and a material of the orifice forming member is caused to flow from an entire circumference at a downstream end portion of the orifice hole to an inside of the orifice hole, whereby the first recess portion having an inner diameter larger than that of the orifice hole is formed on the bottom surface of the second recess portion, and a cross-sectional area reducing portion in which a cross-sectional area of the orifice hole is reduced from an upstream side to a downstream side is formed in the downstream opening portion of the orifice hole.

15

2. The working method of an orifice according to claim 1, wherein the orifice hole has a circular cross section.

3. The working method of an orifice according to claim 2, wherein, in the second step, a first recess portion is formed in a downstream opening portion of the orifice hole together with the cross-sectional area reduction portion, the first recess portion having an inner diameter larger than an inner diameter of the orifice hole.

4. The working method of an orifice according to claim 3, wherein

a communication hole is formed between the first recess portion and the cross-sectional area reduction portion, the communication hole having an inner diameter which is substantially uniform in a direction along a center axis of the orifice hole, and

the inner diameter of the communication hole is equal to a minimum inner diameter of the cross-sectional area reduction portion.

5. The working method of an orifice according to claim 4, wherein the communication hole is formed with formation of the first recess portion and the cross-sectional area reduction portion in the second step.

6. The working method of an orifice according to claim 3, the working method further comprising

a third step of forming a second recess portion having a bottom surface in which an outlet opening portion of the orifice hole opens, before the orifice hole is formed, wherein an inner diameter of the second recess portion is larger than the inner diameter of the orifice hole.

7. The working method of an orifice according to claim 6, the working method further comprising

16

a fourth step of forming a third recess portion having a bottom surface in which the second recess portion opens, before the second recess portion is formed, wherein an inner diameter of the third recess portion is larger than the inner diameter of the second recess portion.

8. The working method of an orifice according to claim 3, wherein

a second recess portion is press-formed in a spherical portion provided at a tip end of the orifice forming member,

in the first step, the orifice hole is press-worked into a cylindrical shape on a bottom surface of a work-hardened second recess portion, and

in the second step, the bottom surface of the second recess portion in which the orifice hole opens is press-worked to form the cross-sectional area reduction portion.

9. The working method of an orifice according to claim 8, wherein when the inner diameter of the orifice hole is set as d, and a length formed between an intersection between a center axis and an inlet opening surface of the orifice hole before the cross-sectional area reduction portion is formed and an intersection between the center axis and an outlet opening surface of the orifice hole, on the center axis of the orifice hole, is set as L, the orifice hole is formed to satisfy a relation of $L/d \geq 1.5$.

10. The working method of an orifice according to claim 9, wherein

in the second step, the cross-sectional area reduction portion is formed by press-working the convex portion into a substantially flat shape.
